Primary Examiner — T. Chase Nelson*Assistant Examiner* — Michael A Pratt(74) *Attorney, Agent, or Firm* — Barlow, Josephs & Holmes, Ltd.(57) **CLAIM**

The ornamental design for a low profile flip up sight, as shown and described.

DESCRIPTION

FIG. 1 is a perspective view of the low profile flip up sight in accordance with the present invention;

FIG. 2 is a rear view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The elements depicted in broken line in the various figures are included for environmental purposes only, and form no part of the claimed design.
